(57) CLAIM

The ornamental design for a connecting element, as shown and described.

DESCRIPTION

FIG. 1 is a perspective view of a connecting element showing my new design which is also a mirror image of the opposite side thereof;

FIG. 2 is a front plan view thereof;

FIG. 3 is a side plan view thereof which is a mirror image of the opposite side thereof; and,

FIG. 4 is a top plan view thereof.

Any undisclosed surface area in any figure is without ornamentation.
